US00D904454S

(12) **United States Design Patent** (10) **Patent No.:** **US D904,454 S**
Suki (45) **Date of Patent:** **** Dec. 8, 2020**

(54) **DISPLAY PANEL OR SCREEN OR PORTION THEREOF WITH GRAPHICAL USER INTERFACE**

(71) Applicant: **SONY CORPORATION**, Tokyo (JP)

(72) Inventor: **Yasuyuki Suki**, Tokyo (JP)

(73) Assignee: **SONY CORPORATION**, Tokyo (JP)

(**) Term: **15 Years**

(21) Appl. No.: **29/693,665**

(22) Filed: **Jun. 4, 2019**

Related U.S. Application Data

(63) Continuation of application No. 29/558,355, filed on Mar. 16, 2016, now Pat. No. Des. 855,629.

(57) **CLAIM**

The ornamental design for a display panel or screen or portion thereof with graphical user interface, as shown and described.

DESCRIPTION

FIGURE is a front view of a display panel or screen or portion thereof with graphical user interface showing my new design.

The outermost broken line rectangle illustrates a display panel or screen or portion thereof. The remaining broken lines illustrate portions of the graphical user interface. None of the broken lines form part of the claimed design.

1 Claim, 1 Drawing Sheet
